UNITED STATES PATENT OFFICE.

SOPHIE STIEBEL, OF PHILADELPHIA, PENNSYLVANIA.

DESIGN FOR A BICYCLE DRINKING-CUP.

SPECIFICATION forming part of Design No. 27,379, dated July 20, 1897.

Application filed June 16, 1897. Serial No. 641,071. Term of patent 7 years.

To all whom it may concern:

Be it known that I, SOPHIE STIEBEL, a citizen of the United States, and a resident of the city and county of Philadelphia, State of Pennsylvania, have invented and produced a new and original Design for Bicycle Drinking-Cups, of which the following is a specification, reference being had to the accompanying drawings, forming part thereof.

10 Figure 1 is a perspective view of my drinking-cup, and Fig. 2 a central longitudinal section of the same.

The leading feature of my design lies in the particular form of the body of the cup. 15 Its back A is straight, its mouths, of which there are two, are circular, as shown at B B', and its sides C C', other than its back B, taper inwardly, as shown, from its mouths to

its center or to the partition D, which divides the body transversely and forms two 20 cups in one body.

A further feature of my design is a ring E by means of which the cup may be suspended.

It will be obvious that the exterior of the 25 cup may be engraved in any suitable manner.

Having thus described my invention, I claim as new and desire to secure by Letters Patent—

The design for a drinking-cup as herein 30 shown and described.

SOPHIE STIEBEL.
